UNITED STATES PATENT OFFICE.

WALLACE I. STIMPSON, OF MILFORD, MASSACHUSETTS, ASSIGNOR TO DRAPER COMPANY, OF PORTLAND, MAINE, AND HOPEDALE, MASSACHUSETTS.

DESIGN FOR A WARP-STOP-MOTION DETECTOR.

SPECIFICATION forming part of Design No. 34,624, dated June 4, 1901.

Application filed May 2, 1901. Serial No. 58,550. Term of patent 14 years.

To all whom it may concern:

Be it known that I, WALLACE I. STIMPSON, a citizen of the United States, residing at Milford, in the county of Worcester and State of Massachusetts, have invented and produced a new, useful, and original Design for a Warp-Stop-Motion Detector, of which the following is a specification, reference being had to the accompanying drawings, forming a part thereof.

Figure 1 is a side elevation of a warp-stop-motion detector, illustrating my design; and Fig. 2 is an edge view thereof.

The leading feature of my design for a warp-stop-motion detector consists of a thin flat body having at one end a narrower elongated neck terminating in an enlarged head, the neck having a longitudinal slot therein extended into the head.

The warp-stop-motion detector embodying

my design consists of a thin flat body a , having at one end an elongated neck a' , of less width than the body, the neck terminating in an enlarged head a^2 , into which is extended the upper end of a longitudinal slot a^3 in the neck.

Having fully described my invention, what I claim, and desire to secure by Letters Patent, is—

The design for a warp-stop-motion detector, substantially as shown and described.

In testimony whereof I have signed my name to this specification in the presence of two subscribing witnesses.

WALLACE I. STIMPSON.

Witnesses:

GEORGE OTIS DRAPER,
ERNEST W. WOOD.
